(57) **CLAIM**

The ornamental design for a tape spool support for tape cartridge, as shown and described.

DESCRIPTION

FIG. 1 is a perspective view of a tape spool support for tape cartridge from one side;

FIG. 2 is a perspective view thereof from another side;

FIG. 3 is a top view thereof;

FIG. 4 is a front view thereof; and,

FIG. 5 is a rear view thereof.

The bottom, left side and right side views contain no ornamentality and are omitted. The broken lines define the bounds of the claimed design, but do not form part of the claimed design.
